UNITED STATES PATENT OFFICE.

ISAAC KAUFMANN, OF NEW YORK, N. Y.

ALBUM-STAND.

SPECIFICATION forming part of Letters Patent No. 508,224, dated November 7, 1893.

Application filed August 1, 1893. Serial No. 482,063. (No model.)

To all whom it may concern:

Be it known that I, ISAAC KAUFMANN, a citizen of the United States, residing in the city of New York, in the county and State of 5 New York, have invented certain new and useful Improvements in Album-Stands, of which the following is a specification.

This invention has reference to an improved stand for photograph albums by which 10 the same can be adjusted in inclined or horizontal position, so as to permit the convenient inspection of the same.

The invention consists of a stand for photograph albums, composed of a base, a photograph album hinged to the upright portion 15 on the base, and a spring-actuated stay that is pivoted to the base and provided at its upper end with a pivoted handle that is guided in eyes at the under side of the album, said 20 handle being provided with means for locking the album in horizontal position on the support or in inclined position, as will be fully described hereinafter and finally pointed out in the claims.

25 In the accompanying drawings, Figures 1 and 2 represent perspective views of my improved album-stand, showing the same respectively in inclined and horizontal position. Figs. 3 and 4 are side elevations respectively 30 of Figs. 1 and 2, drawn on a larger scale, and Fig. 5 is a sectional plan view of the device for holding the album in inclined or horizontal position.

Similar letters of reference indicate corresponding parts.

Referring to the drawings, A represents a stand which is formed of a horizontal base portion *a* and a vertical portion *a'*.

35 B represents a photograph or other album, 40 the bottom part of which is hinged to the upper end of the vertical portion *a'*, as shown clearly in Fig. 4.

The album B is preferably of the same material as the base of the stand so that an ornamental appearance is imparted to the structure. The album may be of any desired construction, and adapted to be opened either at its lower part or at either side as desired, it being provided with a spring clasp *b*.

45 50 To the base *a* of the stand A is hinged a

stay C which is preferably made of sheet-metal of suitable strength, and which is connected by a helical spring C' with the upright portion *a'* of the frame A. To the upper end of the stay C is pivoted a handle D, which is 55 made of wire and which is preferably bent into U-shape and which is guided in eyes *d* or other suitable devices attached to the underside or bottom of the album B. The outer end of the handle D is bent so as to fit quite 60 closely to the edge of the album when the same is supported in inclined position, as shown in Figs. 1 and 3, in which position the stay assumes an inclined position from the base toward the upright portion *a'*. 65

When it is desired to support the album in horizontal position or nearly so, the same is lifted against the tension of the spring C' of the stay C, which is accomplished by pulling the handle D in the forward direction through 70 the eyes until the bent or nicked portion *e* of the handle arrives in front of the front guide eyes *d*, as shown in Fig. 4, in which position the album is supported on the upright portion *a'* and the stay C, and held securely by the locking action of the handle so that the album can be opened and the pictures in the same inspected. When it is desired to return the album to the inclined position, the handle D is pushed in upward direction, so that the nick in the same 80 clears the eye, whereupon, by the action of the spring, the album and its supporting stay are immediately returned into position, as shown in Fig. 3.

Having thus described my invention, I 85 claim as new and desire to secure by Letters Patent—

1. The combination, with a supporting stand, of an album hinged to an upright portion of the stand, a spring-actuated stay hinged to 90 the base of the stand, a handle pivoted to the upper end of the stay and guided along the bottom of the album, and means for locking the handle to the album so as to support the same in horizontal position on the upright 95 portion and stay, substantially as set forth.

2. The combination, with a supporting stand, of an album hinged to an upright portion of the stand, a spring-actuated supporting stay hinged to the base of the stand, and a handle 100

pivoted to the upper end of the stay and guided in eyes attached to the bottom of the album, said handle being provided with nicks by which it can be locked in position so as to support the album in horizontal position or nearly so, substantially as set forth.

In testimony that I claim the foregoing as

my invention I have signed my name in presence of two subscribing witnesses.

ISAAC KAUFMANN.
